SAG ELIMINATING ATTACHMENT FOR CRANK SHAFT GRINDING MACHINES

Application filed September 24, 1930. Serial No. 484,180.

This invention relates to an attachment for crank shaft grinding machines to counteract the sagging which is usual in such machines.

A primary object of the invention is to so construct a device of this character, the use of which adapts the machine to which the device is applied to grind the crank so nearly round that it will be practically impossible to detect any error by a micrometer.

10 A crank shaft is much more easily sprung in one direction than another and as a result sag of the shaft causes the pin to raise and lower as it is revolved while being ground and without the use of rests of any kind it is practically impossible to grind a shaft that would be closer than four or five thousandths of an inch from being round. All grinding machines are equipped with rests intended to correct this error by holding the pins stationary, but it has heretofore been found impossible to obtain crank pins that are round to the same degree that plain cylindrical grinding can be made round with any of the rests provided for this work.

25 It is to overcome this objectionable feature that this invention is designed and by the use of which as stated above cranks may be ground so nearly round that it is impossible to detect any error even with a micrometer.

30 In carrying out these objects, the invention is susceptible of a wide range of modification without departing from the spirit or sacrificing any of the advantages of the claimed invention; there being shown in the drawings 35 for illustrative purposes a preferred and practical form, in which:

Figure 1 represents a side elevation of a grinding machine equipped with this improved sag eliminating attachment;

40 Fig. 2 is a top plan view thereof with parts broken out for convenience in illustration;

Fig. 3 is a vertical section taken on the line 3—3 of Fig. 1;

Fig. 4 is a similar section taken on the line 45 4—4 of Fig. 3;

Fig. 5 is a sectional view taken on the line 5—5 of Fig. 3; and

Fig. 6 is a detail perspective view of the lever fulcrum used in connection with the 50 attachment.

In the embodiment illustrated the attachment constituting this invention is shown applied to a shaft grinding machine known on the market as a "Norton Autopart" but it is to be understood that it is adapted for any grinding machine of this character by slight changes in the weight and lever carrying members. This machine 1 includes a grinding wheel 2 so mounted that the periphery thereof will engage the portion of the crank 55 shaft which is to be ground and which is shown in Fig. 2 as 3, the entire crank shaft being numbered 4.

The attachment 10 constituting this invention comprises a two-piece disk 11 the members or sections 12 and 13 of which have their opposed edges cut away for a portion of their length to form when united a recess 14 (see Fig. 3). These sections are securely held in operative position by means of a key 15 which permits the sections to be separated for the mounting of the disk on the crank shaft 1 to be ground. Attached to one face of the disk 11 is what is termed a V-block 16 by means of which the disk is designed to be adjustably mounted and clamped on the shaft.

Designed to fit around the V-block 16 is what is termed a strap clamp 17 which is U-shaped in form, the legs 18 of which are threaded at their free ends to receive securing nuts or sleeves 19 between which and shoulders 20 on said legs 18 is a clamping cross bar 21 apertured at its ends for the passage therethrough of the threaded portions of the clamp member 17. Extending parallel with the cut out portion 14 of the disk 11 at opposite sides thereof are two slots 22 and 23 designed to receive bolts 24 which extend through the V-block 16 and adjustably secure it to the disk 11.

Designed to cooperate with the disk 11 which is adapted to be mounted on the crank shaft to be ground in a manner presently to be described is a short lever 25 fulcrumed at one end on a bracket 26 which is adjustably mounted in a T-slot 6 of the machine table. It is to be understood that this mounting is accomplished by means of a T-headed bolt 27 the head of which is designed to be mounted in the slot 6 and which is equipped at its 60 65 70 75 80 85 90 95 100 105

outer end with a nut 28 for securely locking the bracket in operative position.

A seat 29 is secured to the upper face of the lever 25 near its free end and is shaped 5 to conform to the periphery of the disk 11 in connection with which it is to be used. This seat 29 is designed when the device is applied to be exactly under the center of the disk 11 and is held in this position by means now to 10 be described.

A casting 30 shown in detail in Fig. 6 is designed to be bolted to the machine table 6 as is shown in Fig. 3 and is designed to operate as a fulcrum for a long weight carrying 15 lever 40. This lever 40 is designed to extend under the free end of the disk engaging lever 25 and hold it with the seat 29 engaging the disk.

The casting or bracket 30 extends transversely of the machine table 5 parallel with the lever 25 and is clamped to the table by means of an inturned lip 31 at one end of said bracket and an L-shaped bolt 32 spaced from said lip and extending obliquely so 25 that it may be securely engaged with an undercut lug of the table 5. Extending upwardly from the other end of the casting 30 are two longitudinally spaced standards 33 and 34 provided with registering notches or 30 bearings 35 designed to receive pintles 41 which project laterally from opposite faces of the lever 40 and form a fulcrum for said lever. The upstanding standards 33 and 34 form guides for the lever to prevent its lateral 35 displacement. The front end of the lever 40 is offset from the remainder and the rear portion of the lever is provided throughout its length with a graduation indicating 40 pounds to disclose the force of the weight 43 which is adjustably mounted on the graduated end of the lever and which is secured in adjusted position thereon by means of a set screw 34.

It will thus be seen that the lever 40 extends in a plane at right angles to the lever 25 and they are so mounted that they do not interfere with the use of the regular rests provided with machines of this character.

In the use of this attachment the crank 50 shaft 1 is clamped to the throw-out blocks 7 in the usual manner with the pin centered and set up for grinding by the wheel 2 exactly as it would be if this attachment were not used. When the crank shaft has been so set 55 up the V-block 16 is clamped to the center main bearing by means of the strap clamp 17 being set parallel with the throw-out blocks 7. The two-piece disk 11 is then clamped to the V-shaped block 16 by means 60 of the two bolts 24 and is moved in or out and adjusted until it will run approximately true, the slots 22 and 23 providing for the setting of the disk at any stroke desired. When the disk and the V-block have been 65 clamped to the shaft 1 the weight carrier 30

is clamped to the bed of the machine and the lever 25 is set with the seat 29 thereof exactly under the center of disk 11. The weight 43 is then adjusted to suit the particular shaft being ground and will operate to hold such 70 shaft against sagging thereby adapting the shaft to be ground as nearly round as possible so that no errors may be detected in this respect even with a micrometer.

Without further description it is thought 75 that the features and advantages of the invention will be readily apparent to those skilled in the art, and it will, of course, be understood that changes in the form, proportion and minor details of construction 80 may be resorted to, without departing from the spirit of the invention or its scope as claimed.

I claim:

1. A sag eliminating attachment for crank 85 shaft grinding machines comprising a disk having means for adjustably mounting it on the shaft to be ground, pressure exerting means for engaging the periphery of said disk, and means for controlling pressure exerted by said pressure means to overcome the sag caused by the weight of the shaft and the pressure of the grinding wheel thereon.

2. A sag eliminating attachment for crank shaft grinding machines comprising a member 95 having means for adjustable mounting on a shaft to be ground means for exerting pressure on said member in a direction against the sagging tendency of the shaft, and means for controlling the pressure exerted by said pressure means.

3. A sag eliminating attachment for crank shaft grinding machines comprising a member having means for adjustable mounting on a shaft to be ground, means for exerting pressure on said member in a direction against the sagging tendency of the shaft, a lever for engaging said pressure exerting means, and means for varying the force exerted by said lever on said means whereby the sagging tendency of the shaft being ground is controlled.

4. A sag eliminating attachment for crank shaft grinding machines comprising a separably connected sectional disk, means for 115 mounting said disk on a shaft to be ground and for adjusting it relatively to said shaft, a pressure exerting lever engaging the periphery of said disk, another lever engaging said first mentioned lever, and means on the 120 last mentioned lever for varying the pressure on the disk for controlling the sagging tendency of the shaft.

5. A device of the class described comprising a separably connected sectional disk having an enlarged elongated opening for the passage of the shaft to be ground, a V-block 125 adjustably mounted on said disk, means for clamping said block to the shaft to be ground, a lever fulcrumed at one end on a support 130

and having its free end engaging the periphery of said disk, and another lever extending at right angles to the first mentioned lever and supporting it, and pressure means for causing the last mentioned lever to forcibly engage the first mentioned lever and hold it engaged with the periphery of the disk.
